CONVEYING AND LOADING MECHANISM

Nils D. Levin, Columbus, Ohio, assignor to The Jeffery Manufacturing Company, Columbus, Ohio, a corporation of Ohio

Application November 17, 1931, Serial No. 575,621

9 Claims. (Cl. 198—3)

The present invention relates to apparatus for gathering material lying in an elongated pile and delivering the material to a point preferably at one end of the pile. The invention finds particular application in mines wherein material is removed in successive increments of considerable length, as in the "longwall" system of mining.

According to the "longwall" system, the wall of the mine room is kerfed to a certain depth throughout its length, or a considerable portion thereof, and the kerfed material shot down, the disrupted material lying in a pile extending along the newly exposed face.

According to the present invention, for the purpose of removing the disrupted material an elongated stationary conveyor is disposed parallel to the face and spaced from the material a sufficient distance to permit a gathering instrumentality to travel between the conveyor and mine face, gather the material, and pass it to the stationary conveyor for delivery thereby to the room entry. In its travel the gathering conveyor is guided by guiding means presented by the adjacent edge of the stationary conveyor. Features of novelty reside in both conveyors and in their combination, as will be pointed out in the claims.

In the accompanying drawings which illustrate a practical embodiment of the invention,

Figure 1 is a plan view of a suitable form of gathering conveyor,

Figure 2 is a side elevation of the conveyor of Figure 1,

Figure 3 is a section on line 3—3 of Figure 1 and includes a cross sectional view of the stationary conveyor,

Figure 4 is a section on line 4—4 of Figure 3,

Figure 5 is a section on line 5—5 of Figure 4,

Figure 6 is a section on line 6—6 of Figure 2,

Figure 7 is a section on line 7—7 of Figure 6,

Figure 8 is a plan view of the conveyors in operative arrangement in a mine,

Figure 8a is an enlarged view of a detail of Figure 8, and

Figure 9 is a perspective view of a guide rail associated with the stationary conveyor.

Referring to the drawings, reference number 10 designates generally a gathering conveyor which comprises a main casting 11 and plates 12 and 13. The plate 12 is elongated and has a projecting substantially horizontal bed or way 13 and an upwardly inclined bed or way 14, Figs. 1, 2 and 3.

Spaced guide members 15 and 16 extend longitudinally of plate 12 in symmetrical relation to the longitudinal axis of the plate, these guide

members serving to guide an endless draft device in the form of a chain 17 made up of links pivoted together to render the chain flexible in both horizontal and vertical planes. Scraper flights 18 are secured to the chain 17 at intervals and travel over the beds or ways 13 and 14. The ends of the flights, it will be noted, project beyond the lateral edges of the bed or way 13 of the plate 12 but terminate inwardly of the lateral edges of the inclined bed or way 14, the edges of the latter being contiguous with the lower edges of outwardly flared guide plates 19 and 20.

Journalized in a vertical sleeve 21 of the main casting 11 is a head shaft 22 upon which is rotatably mounted a sprocket wheel 23 engaging chain 17 to drive the latter. The sprocket wheel is provided with a lower sleeve portion 24 and within the latter are clutch teeth 25 adapted to be engaged by clutch teeth 26 formed on a sleeve 27 splined on the lower end of shaft 22 and held thereon by means of a plate 28. Sleeve 27 is provided with a circumferential groove 27' in which is engaged a half ring 29 provided with diametrically opposite trunnions as at 30, Figure 3, engaged in the bifurcated ends of the yoke arms 31. The yoke is fixed on a rocking pin 32 to which is also fixed an arm 33 provided with spaced fingers 34 and 35 at its extremities. Pin 32 is supported in bracket members as at 36. A shaft 37 has an eccentric central portion 38 engaged between the fingers 34, 35, the shaft 37 comprising two coaxial terminal portions journaled in blocks as at 39 and 40, Figure 3, at opposite sides of the machine, the extremities of the shaft being angularly bent and constituting levers, one of which is shown in dotted lines at 161, by means of which the shaft may be rocked to engage the clutch teeth 26 with the teeth 25 or to disengage them therefrom.

Above the sprocket wheel 23 a gear 41 is keyed to shaft 22 and is engaged by a drive pinion 42 fixed on a drive shaft 43 journaled in a portion 44 of the casting 11 in conjunction with a semi-circular block 45, Figures 3 and 4, between which is positioned a thrust flange 47 integral with shaft 45 43 and accessible upon removal of the cover plate 46. Shaft 43 is coaxial with the armature shaft of a reversible electric motor 48 mounted on a platform 49 of the casting 11, Figure 2, suitable coupling means for the shafts being provided.

Rotatable on an upwardly extending cylindrical boss portion 41' of gear 41 is a ring 50 provided with a plurality of upwardly extending studs 51, 52 and 53 upon which are rotatable planet wheels 55

54, 55 and 56, all of which are engaged by a sun pinion 57, here shown as being formed integral with shaft 22. Above pinion 57 a drum 58 is journaled on shaft 22 and is held thereon by means 5 of a cap plate 59. Secured to the lower margins of the drum flange 60 is a ring gear 61 which is engaged by the planet wheels 54, 55, 56. Gear 41 and ring 50 are provided with registerable key ways 62 and 63 in which a key 63' is insertable 10 to lock the two elements together. Under these circumstances it will be evident that since ring 50 will rotate at the speed of shaft 22, drum 58 will also rotate at the speed of the shaft.

A brake band 64 provided with a friction liner 15 65 has lugs 66 and 67 secured to its ends, as shown in Fig. 4, these lugs being provided with outer substantially parallel faces against which bear cap screws 68 and 69 threaded through ledges 70 and 71 of the main casting 11. Key 63' 20 may be removed from its locking position above described whereupon the drive of drum 58 may be controlled by suitably tensioning brake band 64. When key 63' is not in use, it may be placed in an aperture provided in a plate 72, Figure 3, to 25 assume the dotted line position shown.

With gear 41 and ring 50 locked together, drum 58 is rotated at a definite relatively high speed which is the speed of shaft 22, as above mentioned. With ring 50 revoluble relative to gear 30 41 but held stationary by means of the brake band, drum 58 will be rotated at a definite relatively slow speed. By loosening the brake band to permit slipping of the ring 50, still slower speeds of drum 58 may be secured.

35 Drum 58 is provided with an annular lubricant chamber 73 having an annular cover plate 74 provided with an opening (not shown) through which lubricant may be introduced. The bottom of the chamber is provided with apertures as at 40 73' overlying cup-like formations 75 of ring 50, the latter communicating through ducts 76 with the top of boss portion 41' to supply lubricant thereto. Lubricant is also supplied through ducts 73' to the tops of planet wheels 54, 55 and 56 to 45 supply lubricant to the bearings thereof, surplus being carried by centrifugal force to the teeth of ring gear 61 to bathe the latter in lubricant. Downwardly escaping lubricant is caught in cup-like formations of the ring 50 as at 77, Figure 3, 50 whence it passes through ducts as at 78 to lubricate further contacting surfaces of the gear and ring.

Disposed between the motor and the drum is a casting 79 mounted on the main casting 11 and secured thereto by means of bolts. Casting 79 supports a sheave 80 on a vertical axis to one side of the longitudinal axis of plate 12 and in a suitable plane to receive a cable 81 from drum 58. The casting 79 supports a sheave 82 on a horizontal axis on the opposite side of the longitudinal axis of plate 12 from sheave 80 and positioned to receive cable 81 from sheave 80. The main casting 11 supports a sheave 83 whose central transaxial plane is coincident with the longitudinal axis of plate 12, cable 81 being guided to sheave 83 by means of a sheave 84 positioned beneath sheave 83, the path of the cable between the last mentioned sheaves being clear of the opening 85 through which the drive shaft 43 extends.

70 A bar 86 extending beneath plate portion 14 transversely thereof supports at its central portion the adjacent sheaves 87 and 88 for rotation about vertical axes and at its ends the bar supports similar sheaves 89 and 90. Sheaves 87 and

88 are positioned to receive the cable 81 from sheave 83. As shown in Figure 1, the cable is reaved about sheaves 87 and 88. If, however, it is desired to reverse the direction of movement of the conveyor, the cable is reaved about sheaves 88 and 90.

Forwardly of motor 48 a cover plate 91 extends between guide members 15 and 16 and mounted thereon is an upright baffle plate 92 surmounted by a horizontal baffle plate 93. A post at the 10 forward end of plate 92 presents upwardly extending spaced fingers 94 and 95. The motor is protected by forwardly divergent baffle plates 96 and 97.

A bracket 98, Figures 1, 6 and 7, has an arm 99 15 slidably engageable in a sleeve 100 secured beneath the bed or way 101, the arm being securable in such position by means of a pin 102 passed through the top plate 103 of the sleeve and engaged in an aperture 104 of the bracket. Bracket 20 98 has an integral stud 105 upon which is rotatable a drum 106, the drum having a brake flange 107 spaced within a protecting wall 108 of the bracket and adapted to co-act with a brake band 109. The drum 106 is rotatable by means of a 25 crank handle 110 and has one end of a cable 111 secured thereto.

Band 109 has lugs 112 and 113 at its free ends, the lugs presenting parallel outer surfaces engaged respectively by the cap screw 114 and the 30 screw spindle 115 with which is integral a disc 116 and a shank 117. A lever 118 is pivoted on shank 117 outwardly of disc 116 and is pressed toward the latter by means of a compression spring 119 interposed between the lever and an 35 abutment washer 120 at the extremity of the shank. Disc 116 has a number of spaced lugs as at 121 and 122 on its outer face between which lever 118 is adapted to seat and through abutment therewith to transmit rotary movement to 40 the spindle 115 in either direction. The angular position of the lever 118 relative to the screw spindle may be altered by moving the lever outwardly of the shank against the force of spring 119, swinging it relative to the shank and permitting it to seat between another pair of lugs. Obviously through proper manipulation of the lever 118 the tension of band 109 may be regulated. Drum 106 is intended for use as a retarding drum and hence must be disposed on the 50 trailing side of the conveyor so as to be accessible to the operator. Band 64 must be controllable from a similar station, and to this end I provide an elongated socket member 123 adapted to engage the head of cap screw 68 or 69, the socket 55 member at its other end being provided with a hand wheel 124 and having a constricted portion 125 inwardly of the hand wheel engaged in an upwardly open notch in a clip 126 secured to the upper edge of wall 19. According to Figures 1, 2 60 and 8, it will be seen that the hand wheel 124 is directly above drum 106, the socket member being engaged with the head of cap screw 69.

Beneath the guard plate 127 is disposed a starting box 128 while beneath the guard plate 129 65 at the same side of the machine is disposed a reversing switch 130, an electric supply cable 131 being engaged in a clip 132 on plate 129 and led to a junction box 133 at the top of the motor through a belled neck portion 134.

If the machine is to be moved in the opposite direction from that contemplated in Figures 1 and 8, cable 81 is reaved over sheaves 88 and 90, bracket 98 is dismounted and remounted at the other side of the machine with arm 99 engaged 75

in a sleeve 135, and the socket member 123 is engaged with the head of cap screw 68 so that hand wheel 124 is brought above the new position of drum 106, the constricted portion 125 of the socket member being engaged in an upwardly open recess of a clip 136. The starting box and reversing switch are duplicated on the opposite side of the machine and a clip 137 is provided for engaging the electric cable 131.

10 The stationary conveyor is designated generally at 138, Figures 3 and 8, and as here shown is made up of a series of sections as 139, 140 and 141, the conveyor being disposed in substantially parallel relation to the mine face 142, a mass of disrupted material being shown in front of the face at 143.

15 Each conveyor section comprises channel side members as at 144 and 145, Figure 3, a bottom plate 146 and a partition plate 147, the top and bottom runs of an endless draft device traveling respectively above and below the partition plate. The channel members have angle bars as at 148 and 149, Figure 8a, secured in vertical position adjacent their ends and provided with apertures through which connecting bolts as at 150 are passed to secure the sections together.

20 In order to provide a substantially continuous and adequate guide surface for the gathering conveyor, I provide a number of channel members as at 151 each preferably of the same length as each conveyor section and provided adjacent their ends with apertures as at 152 and 153 (Fig. 9). However, if desired the length of each channel member may be a multiple of the length of each conveyor section. The channel members are disposed with their ends in embracing relation to the angle bars 148, 149 at the ends of the sections, and pins, as at 154, are passed through the apertures 152 and 153 between bolts 150 and side members 145 to retain the channel members 151 in alignment. The members 151 in alignment constitute a continuous guide rail adapted to be engaged by the vertical plate 155 at the rear of the gathering conveyor, this plate being 25 V-shaped in plan as shown in Fig. 1 to afford a fulcrum for the purpose hereinafter explained. The lower horizontal plate portion 101 of the frame 11 overhangs the stationary conveyor to deliver thereto, material confining plates 160 being mounted on the side wall 144.

30 Inasmuch as the guide rails are detachable they may be removed one after another after the gathering unit has passed by, and re-attached to the conveyor in advance of the gathering apparatus. 35 In some instances, two guide rails each of the same length as a conveyor section may be sufficient; or, if desired, one guide rail may be used of a length equal to the combined lengths of two conveyor sections. Such double length guide rail may be disconnected and slid along the conveyor to a new position each time the gathering unit reaches the next advanced conveyor section.

40 In operation, cable 81, assuming that the gathering conveyor is to be moved as shown in Figure 8, is passed around a sheave 156 supported by a roof jack 157 disposed in advance of the gathering conveyor and is then engaged between the fingers 94 and 95 at the leading end of baffle plate 92. Cable 111 is wound on drum 106 through 45 rotation of the latter by means of crank handle 110 and the free end of the cable is secured to a jack 158 at the rear of the gathering conveyor. Drum 58 is now rotated at slow speed through 50 suitable manipulation of band 64 and band 109 55 70 75 is controlled so that cable 111 is drawn out at

such a rate as to maintain the gathering conveyor in substantially perpendicular relation to the stationary delivery conveyor.

5 It should be noted that the gathering edges of the plate 12 are in alignment with the edges of the pan 159 as shown in dotted lines in Fig. 1. Therefore, since the projecting sides of the rear end of the framework of the gathering conveyor are in elevated positions the gathering unit as a whole is free to tilt in opposite directions to a limited extent to keep the gathering edge in contact with the surface from which the coal is being loaded and prevent such edge from riding up over the loose coal. When the rope gearing is arranged as shown in Fig. 8 the pull on the rope is 10 such that tilting will be effected at the elevated connection 94, 95; furthermore, the location of the anchorage 157 may be such as to secure a resultant force tending to hold the rear end 155 of the frame of the gathering unit against the 15 sectional guide rail which is detachably secured to that side of the conveyor 138 facing the working face 142 of the coal vein.

20 While I prefer to guide the rope 81 over the pulleys 80, 82, 83, 87 and 89 as shown in Fig. 1 25 so as to cooperate with the retarding rope drum 106 in the manner illustrated in Fig. 8, it is evident that when increased leverage for tilting the gathering unit is desired the rope 81 may be extended to the anchorage 157 from the top of the 30 gathering unit, from the rope drum 58 in either direction. It is therefore desirable to mount the rope drum 58 on the uppermost side of the gathering unit.

35 It should be understood that the gear 41 is keyed to the head shaft 22 so that when the clutch 25, 26 is in, power will be transmitted from the motor shaft 43 whether the rope drum 58 is being rotated or not.

40 The rope drum 58 is journaled loosely on the 40 upper end of the head shaft 22 and is therefore coaxial therewith. It can readily be seen that when the brake band 64 is released from the ring 59 the rope drum 58 will not be rotated when the pinion 57 is rotated with the vertical head shaft 45 22. When the rope drum 58 is stationary and the ring 59 is free the planet gears 54, 55, 56 simply walk around the inner annular gear 61 on the rope drum 58. When, however, the brake 64 is partially applied to the ring 59 the rotation of the 50 latter is retarded and consequently power is transmitted to the rope drum 58. The greater the application of the brake 64 to the periphery of the ring 59 the less the slip will be between the brake band and the ring and the greater will be the 55 transmission of power to the rope drum 58. The application of power to the drum 58 may therefore be controlled according to the condition of the coal to be gathered. When the pile of coal is shallow and easily gathered the rope drum may 60 be operated at maximum speed by inserting the key 63' to connect the gear 41 to the ring 59. Then there will be a direct drive to the drum 58 from the gear 41 and the brake band 64 may be 65 kept released while the speed of travel of the gathering unit may be regulated by controlling the motor 43 which is connected to the shaft 43.

70 Through transposition of the parts as above described, the conveyor may gather in either direction of travel, motor 43 being reversible to 70 secure the proper direction of travel of the flights. As has also been mentioned, the working speed of movement of the gathering conveyor is obtained through the planetary transmission between shaft 22 and drum 58. A faster handling speed is ob- 75

tained when band 64 is entirely released and key 63' is engaged in keyways 62 and 63 to lock ring 50 to gear 41.

When handling the gathering unit to position it where desired the clutch 25, 26 may be disengaged by rocking the shaft 37 which may be manipulated from either side of the gathering conveyor. The rope 81 may be removed from the guide pulley 88 or 93 and passed through the rear bottom central passageway formed by the vertical spaced apart plates 161, 162 and the horizontal plate 163. The plate 163 is flared upwardly at its forward and rear ends to facilitate sliding of the rope through the passageway referred to while the free end of the rope is connected to a fixed anchorage in the mine and a pull is being exerted on the rope by direct rotation of the rope drum 58 with the key 63' inserted as shown in Fig. 3. The rear edge of the base plate 159 is beveled at 164 to enable the gathering unit to more easily ride over the floor while it is being handled for positioning purposes. In such handling operation the power operated mechanism on the gathering unit is used to move the latter about in the mine from one place to another and into position at the conveyor 138 as shown in Fig. 8.

It should also be noted that the plate 155 is V-shaped in plan as shown in dotted lines in Fig. 1, therefore, during operation the outer end of the gathering conveyor may have a limited amount of forward and backward swinging movement on the connection between the bearing plate 155 and the guide channel 151 as a fulcrum.

In practice, conveyor 138 will ordinarily be placed in position and a "longwall" machine operated between the conveyor and the mine face to form an underkerf therein. The whole face may be underkerfed and shot down and the mining machine removed and replaced by the gathering conveyor or the gathering conveyor may follow to the rear of the mining machine, the underkerfed material, through suitable means, being continuously dislodged in advance of the gathering conveyor unit. When the gathering conveyor unit is fed in one direction the conveyor 138 may be operated in the same direction or the opposite direction. However, the invention is not limited to any precise mode of procedure since it will adapt itself to various systems of material removal as will be understood by those skilled in the art.

Further, while I have described a specific embodiment of the invention it is to be understood that I do not limit myself to structure except as set forth in the following claims:

1. Apparatus of the class described comprising a receiving conveyor having an elongated frame and on a side of the frame a longitudinally extending rail having an outer lateral guide surface, a side gathering conveyor comprising a frame adapted to move along the receiving conveyor in substantially rectangular relation thereto to discharge thereto, means comprising a winding drum on the gathering conveyor frame for so moving said gathering conveyor and means on the rear portion of said gathering conveyor horizontally pivotal on and movable along said rail to maintain the operative relation of the gathering conveyor to the receiving conveyor.

2. Apparatus of the class described comprising a receiving conveyor having an elongated frame and on a side of the frame a longitudinally extending rail having an outer lateral guide sur-

face, a side gathering conveyor comprising a frame adapted to move along the receiving conveyor in substantially rectangular relation thereto to discharge thereto, means comprising a winding drum on the gathering conveyor frame for so moving said gathering conveyor, and a rearwardly faced shoe on the rear portion of said gathering conveyor having a horizontally convexed face pivotal on and slidable along said rail to maintain the operative relation of the gathering conveyor to the receiving conveyor.

3. A side gathering conveyor comprising a frame including an elongated normally horizontal base plate tilttable about a longitudinal axis to a scraping position with an edge of the base plate in substantially continuous contact with the supporting surface, an endless material moving device having a portion traveling on said plate adjacent said edge, and means for laterally traversing the conveyor substantially translationally and for tilting the conveyor comprising a winding drum on said frame, a draft cable windable on said drum and led from one side of said conveyor at a relatively elevated point, means for rotating the drum to tension the cable and thereby move the conveyor bodily laterally and tilt the base plate about said axis, a snubbing drum on said frame, a cable led from said snubbing drum to an external anchorage at the other side of said conveyor, and means for controlling said snubbing drum to control the tilting angle of said plate.

4. A side gathering conveyor comprising a frame including an elongated normally horizontal base plate tilttable in either direction about a longitudinal axis to a scraping position with an edge of the base plate in substantially continuous contact with the supporting surface, an endless material moving device having a portion traveling on said plate adjacent said edge, and means for laterally traversing the conveyor substantially translationally and for tilting the conveyor comprising a winding drum thereon, a draft cable windable on said drum and adapted to be extended from either side of said conveyor at a relatively elevated point, means for rotating the drum to tension the cable and thereby move the conveyor bodily laterally and tilt the base plate about said axis, a snubbing drum securable to said frame at either side thereof, and a cable windable on said snubbing drum and led to an external anchorage at the opposite side of the conveyor from said first named anchorage, the snubbing drum being secured to said frame on the same side thereof as its associated anchorage, and means for controlling said snubbing drum to control the tilting angle of said plate.

5. A side gathering conveyor comprising a frame including an elongated base plate tilttable about a longitudinal axis to a scraping position, and means for laterally traversing and tilting the conveyor comprising a winding drum on said frame, a draft cable windable on said drum and led from one side of said conveyor at a relatively elevated point, means for rotating the drum to tension the cable and thereby move the conveyor bodily laterally and tilt the base plate about said axis, a snubbing drum on said frame, a cable led from said snubbing drum to an external anchorage at the other side of said conveyor, means for controlling said snubbing drum to control the tilting angle of said plate, and guide means for the conveyor comprising a guide rail extending along the path of movement of said conveyor.

of the conveyor at the delivery end of the latter, said rail having a lateral face toward the conveyor, and abutment means at the delivery end of the conveyor movable on and in contact with 5 said rail face to limit bodily movement of said conveyor in one longitudinal direction while permitting free tilting thereof.

6. A conveyor comprising an elongated frame, an endless draft device guided longitudinally of 10 said frame, an upright head shaft at one end of said frame and projecting upwardly beyond the upper limits of said frame, a wheel on said shaft engaging said draft device to drive the same, a downwardly faced bevel gear on said shaft for 15 driving the same, a motor on said frame, a motor driven shaft having a pinion thereon engaging said gear; and means for moving said frame comprising a winding drum rotatable on the upper extremity of said shaft, planetary gearing 20 between said shaft and drum including a rotary planet carrier disposed between said drum and gear coaxially with said shaft, and means for locking said carrier to said gear to cause rotation of the drum at the speed of the shaft.

7. In combination with a conveyor comprising 25 a plurality of trough sections, the sections being provided at the ends of their side walls with outwardly projecting ears, and bolts connecting the ears at adjacent ends of adjacent sections, 30 rails disposed externally of a side wall of the conveyor and provided with means engageable behind said bolts to secure the rails to the conveyor.

8. In combination with a conveyor comprising 35 a plurality of trough sections, the sections being provided at the ends of their side walls with outwardly projecting ears, and bolts connecting the ears at adjacent ends of adjacent sections, 40 rails disposed externally of a side wall of the conveyor and provided with means engageable behind said bolts to secure the rails to the con-

veyor, said rails being in the form of channel members, in the channels of which said ears are received, said engageable means being in the form of pins received in apertures in the opposite walls of said channel members.

9. A side gathering conveyor comprising a base plate having head and foot portions, the foot portion normally assuming a substantially horizontal position with the head portion elevated thereabove, means beneath and supporting said 10 head portion, the edges of said foot portion being unobstructed and the side plate being tiltable in either direction on the edges of said foot portion and on said supporting means, the lower 15 of said edges upon such tilting being in substantially continuous contact with the supporting surface, an endless flexible draft device mounted for travel longitudinally of said base plate, material engaging flights on said draft device, the advancing and returning runs of said draft device being disposed side by side, an upright head 20 shaft on said head portion, a drive wheel on said head shaft engaging the draft device, said head shaft extending above the remaining conveyor structure, a winding drum on the upper end 25 of said shaft, a motor mounted adjacent the juncture of said head and foot portions above the draft device and closely adjacent thereto, drive connections between said motor and said shaft, a draft cable windable on said drum and 30 led from one side of said conveyor at a relatively elevated point so that upon driving the drum from said shaft to tension the cable the conveyor is moved bodily laterally and tilted, a 35 snubbing drum on the conveyor, a cable led from said snubbing drum to an external anchorage at the other side of said conveyor, and means for controlling the snubbing drum to control the tilting angle of said plate.

NILS D. LEVIN. 40
